UNITED STATES PATENT OFFICE.

EARL W. WELLS, OF PITTSBURGH, PENNSYLVANIA.

PLUG-FUSE.

1,125,612.

Specification of Letters Patent.

Patented Jan. 19, 1915.

Application filed March 6, 1914. Serial No. 822,968.

To all whom it may concern:

Be it known that I, EARL W. WELLS, a citizen of the United States, residing at 950 Beech avenue, Pittsburgh, N. S., in the county of Allegheny and State of Pennsylvania, have invented new and useful Improvements in Plug-Fuses, of which the following is a specification.

This invention relates to improvements in plug fuses for electric currents and has particular application to a refillable plug fuse.

In carrying out the present invention, it is my purpose to provide a fuse of the class described whereby in the event of the fuse wire burning out, such wire may be readily and conveniently renewed or replaced and wherein good electrical contact will be maintained when the fuse is intact.

It is also my purpose to provide a refillable plug fuse which will embrace the desired features of simplicity, efficiency and durability, which may be manufactured and marketed at a minimum expense and which may be quickly and conveniently applied.

With the above and other objects in view, the invention consists in the construction, combination and arrangement of parts hereinafter set forth in and falling within the scope of the claims.

In the accompanying drawing; Figure 1 is a view in elevation of a plug fuse constructed in accordance with the present invention. Fig. 2 is a longitudinal sectional view therethrough. Fig. 3 is a transverse sectional view through the same.

Referring now to the drawing in detail, 1 designates a substantially cup-shaped body preferably composed of insulating material and having the closed end thereof formed with an axial opening 2 and an eccentrically disposed opening 3. These openings are lined with suitable material such as brass rings 4, while threaded into the ring in the axial opening 2 is a contact screw 5. Contiguous the closed end thereof the side wall of the cup-shaped body 1 is screw-threaded and surrounding the same and engaging the threads thereon is an annular shell 6 adapted to be threaded into the socket or receptacle for receiving the fuse plug. The side wall of the body 1 at the upper end thereof is formed with a circumferential bead 7 onto which is threaded

the annular flange 8 of a cap 9, such cap being provided with a transparent window 10 closing the open end of the cup-shaped body 1.

The inner wall of the body 1 is formed with a longitudinal groove 11 and seated within the groove is one limb of a right angular bracket 12, the opposite limb of such bracket extending toward the center of the body and is formed with an aperture into which is threaded a binding screw 13. Formed in the side wall of the body contiguous the lower wall of the groove 11 is an aperture 14 and threaded into such aperture and an opening in the adjacent limb of the right angular bracket 12 is a securing screw 15 having the outer or headed end thereof equipped with a washer 16 bearing upon the adjacent portion of the shell 6 and acting to maintain the latter in position on the body.

17 designates a fusible wire and one end of this wire is wrapped about the shank of the binding screw 13 and secured upon the adjacent limb of the bracket 12 by means of such screw; while the opposite end of the wire is trained through the eccentrically disposed opening 3 and wrapped about the headed end of the contact screw 5 and secured to the body by means of such screw.

From the foregoing description taken in connection with the accompanying drawing, the construction and manner of employing my improved fuse will be readily apparent. The fuse plug is inserted within the receptacle or socket in the usual manner and in the event of a heavy current passing over the line the fusible wire 17 blows out or melts thereby breaking the circuit and protecting the fixtures or translating devices. To replace the fusible wire, the latter is passed through the eccentric opening 3 and the inner end thereof secured to the binding screw 13, while the outer end is fastened in position by means of the contact screw 5. Thus, the fuse plug may be replaced within the receptacle and the circuit re-established.

I claim:

A refillable plug fuse comprising a cup-shaped body having an axial opening and an eccentrically disposed opening in the closed end wall thereof and having a longitudinal groove formed on the inner side thereof, a right angular bracket having one

limb disposed within said groove and the opposite limb disposed in a plane at right angles to the axis of said axial opening, a binding screw carried by the last-mentioned limb, a contact secured within said axial opening, a fusible wire having one end connected with said binding screw and the opposite end passed through said eccentrically disposed opening and secured to 5 said contact, a threaded shell surrounding said body, and a headed securing screw 10 passed through the side wall of said body and engaging the limb of said bracket within the groove and having the head thereof engaging said shell to hold the latter onto the body. 15

In testimony whereof I affix my signature in presence of two witnesses.

EARL W. WELLS.
